(57) **CLAIM**

The ornamental design for a case for cell phones, as shown and described.

DESCRIPTION

1. Case for cell phones

1.1 : Perspective

1.2: Left

1.3 :Top

1.4 : Perspective

The industrial design refers to a case for cell phones (faraday's capsule), which prevents the penetration of any kind of signal.

The broken lines show portions of the case for cell phones that form no part of the claimed design.

1 Claim, 4 Drawing Sheets
